PADDLE WHEEL

Charles R. Melton, Huntington, W. Va.

Application July 20, 1942, Serial No. 451,609

5 Claims. (Cl. 170—141)

This invention relates to marine propulsion and more specifically to paddle wheels.

An important object of the invention is to provide a paddle wheel which will rapidly shed or spill most of the water as the paddles or blades emerge from a body of water, resulting in a saving of horsepower, which is ordinarily lost by the lift of the water.

Another important object is to eliminate substantially all of the usual jerks and vibrations, encountered when paddle wheel blades enter and emerge from a body of water.

Still another important object is to provide strong, sturdy paddle wheels, having detachable blade assemblies, with the blades well braced to prevent their movement from the perpendicular with respect to the periphery of a cylindrical, rotating support.

Another object is to provide a blade unit for a paddle wheel drum, wherein there is no necessity of perforating the drum with bolt-accommodating openings, which might lead to leakage into the drum.

Yet another object is to provide a novel bracing means for the blades of paddle wheels.

The power this novel paddle wheel displays in reverse, affording easy steering for towboats, is another object of the invention, since towboats go into reverse in steering around sharp bends in rivers.

Other objects and advantages of this invention will be apparent during the course of the following detailed description, taken in connection with the accompanying drawings and in which drawings

Figure 1 is an end elevation of the novel paddlewheel illustrating one means for securing the blade assembly to a drum and showing one bracing means for the blades.

Figure 2 is a side elevation of the same.

Figure 3 is a top plan of a blade and associated structure of the blade assembly illustrating one means for securing the several portions of the blade assembly together.

Figure 4 is a front elevation of the showing in Fig. 3.

Figure 5 is a transverse fragmentary section through a blade, intermediate the central portion and one end of the blade.

Figure 6 is a similar view adjacent one end of the blade, illustrating a modified means for attaching the several portions of the blade assembly together.

Figure 7 is an end elevation of a portion of

the novel paddle wheel illustrating a modified bracing means for the blades.

Figure 8 is a view similar to Fig. 7 but shows another modification of the paddle blade bracing means.

Figure 9 is a fragmentary top plan of a blade and associated structure of the blade assembly showing a portion of the modified bracing means of Fig. 8.

Figure 10 is a perspective view of another portion of the bracing means of Fig. 8.

Figure 11 is a longitudinal section of the bracing means of Fig. 8.

In the drawings, wherein for the purpose of illustration is shown preferred and modified forms of the invention and wherein similar reference characters denote like parts in the several views the letter A may designate the paddle wheel of Figs. 1 and 2, as a whole; B, the rotating support for the blade assemblies of all the views; C, the blade assembly of Figs. 1 and 2; D, the blade attaching means of Figs. 3 and 9; E, the blade attaching means of Fig. 6; F, the bracing means of Figs. 1 and 2; G, the paddle wheel of Fig. 7 as a whole; H, the blade bracing means of Fig. 7; J, the paddle wheel of Fig. 8 as a whole; and K, the blade bracing means of Figs. 8 to 11.

The rotating support B may comprise a cylindrical body portion 15, having end walls 16, providing a drum 17 which is preferably water tight and provided with a suitable shaft or pinion 18. A suitable manhole may be provided in one or both end walls 16, each manhole having a cover 19. It will be noted that the cylinder is not perforated and does not include means for attaching the blade assembly thereto, for such means is carried wholly by the several blade assemblies illustrated.

As for the blade assembly or unit C, this includes a plurality (preferably three) of spaced apart, metallic straps or bands 20 and 21, formed into hoops to conform to the curvature or periphery of the cylindrical body portion 15. Preferably, the innermost or centrally disposed strap 21 is wider than the two outermost straps 20, for a purpose later described. As may be seen, at 22, the ends 23 of the straps do not quite meet. Suitably secured to the outer faces of the straps 20 and 21 at these ends 23 is a suitable means to draw and maintain the straps 20 and 21 in tight contact with the periphery or outer face of the cylindrical body portion 15. This means may be angle iron brackets 24, having aligning perforations to accommodate shanks of bolts 25 pro-

vided with suitable nuts 26. These brackets 24 may be welded to the straps 20 and 21, or suitably secured in any approved manner.

The blade assembly C also includes a plurality of spaced apart blades or paddles 27. Each of the blades 27, in horizontal longitudinal section forms an obtuse angle and bridges the straps 20 and 21, so that each blade may be said to form a half blade 28, although each blade is preferably continuous. Forming substantially right angles with each half blade 28 are brackets 29 disposed upon the outer faces of the straps 20 and 21 and may be secured thereto, as by the blade attaching means D, comprising welding, shown at 30 in Fig. 3 and in others of the figures. Since there are two brackets 29, associated with each blade 27, disposed upon the central strap 21, this strap is wider. In order to further strengthen the blade assembly, the brackets 29 may comprise a continuation of the material of the blades 27, with said material continuing as at 31 from each outermost bracket 29 to the nearest of the central brackets 29, as is clearly shown in Figs. 3 and 4. This continuing portion 31, extending from bracket to bracket, together with downturned flanges 32 from the portions 31 constitutes a barrier 33, to prevent water and weeds from sweeping under the blades 27, and interfering with the regular rotation of the paddle wheel. The downturned flanges 32 extend to the periphery or outer face of the cylindrical body portion 15 and from strap 20 to strap 21.

In addition to the blade attaching means D of Fig. 3, heretofore described, the blades may be secured by the means E, of Fig. 6, where each bracket 29 may be provided with a perforation 35 each strap 20 provided with a row, and each strap 21 with a double row of perforations 36 aligning with the perforations 35. The perforations 36 may be beveled as at 37 where they extend to the inner faces of the straps 20 and 21; so that bolts 38 having counter-sunk heads may be employed, with their shanks 39 extending through perforations 35 and 36 and outwardly of the outer faces of the brackets 29, and accommodate suitable washers 40 and nuts 41. Of course, both the means D and E may be employed if desired, on the same paddle wheel blade assembly. Now, as for the novel bracing means F, this is illustrated as a bar or rod 45 of suitable material, formed into substantially a circle, provided with screw threads 46 at its free ends 47 and accommodating a turnbuckle 48. As shown in Fig. 2, two such rods 45 may be provided and the rods extend through suitable slots or openings 49 in the blades 27. Preferably, in order to afford the most bracing effect, the openings 49 are adjacent the outer side edges of the blades 27. When the turnbuckle 48 is employed to contract the circumference of the rod 45, the rod will bear against the walls of the openings 49 nearest the axis of rotations of the paddle wheel.

The paddle wheel G of Fig. 7 is substantially the same as that of the paddle wheel A of Fig. 1 (with either or both of the means D or E employed), the difference being in the blade bracing means.

Blade bracing means H of paddle wheel G, may also comprise a bar or rod 50 of suitable material provided with screw threads 51 at its free ends 52 and accommodating a turnbuckle 53. However the rod 50 is formed, not into a circle, but into a plurality of substantially straight sections 54 extending from blade to blade. Two such rods 50 may be employed, and the rods extend through

slots or openings, similar to the slots or openings 49 in the blades 27. Manipulation of the turnbuckle 53 will have the same effect as described in connection with the means F.

As another modification of the bracing means for the blades, the paddle wheel J of Fig. 8 is provided with the bracing means K of Figs. 8 to 11. Otherwise, the assembly is substantially similar to that of the paddle wheels A and G, but there is a modification of the slots or openings as heretofore described. The slots or openings 55 in the blades 27 of paddle wheel assembly J, may be disposed similarly to those of the openings 49, but each of the openings 55 is provided with a tongue 56 extending outwardly from a wall of the opening 55. This tongue 46 may be an outturned portion of the material removed to provide the opening 55, and has a suitable perforation 57 for a purpose to be described. A bar or strap 58 takes the place of the rod or bar 45, is formed into substantially a circle, and provided with a plurality of spaced apart perforations 59 aligning with the perforations 57 and suitable bolts with their shanks 60 extending through aligning perforations 57 and 59 are secured by washers 61 and nuts 62.

This assembly of blades and bracing means F, H or K, is such that no brace is ordinarily required intermediate the ends of the paddle wheel, with the elimination of an intermediate brace being a decided advantage. The novel bracing tends to draw the blades toward the axis of rotation of the paddle wheel, yet retains the outer ends of the blades properly spaced apart.

Closing the spaces between the straps 20 and 21 and the periphery of the cylindrical body portion 15, prevents strings of weeds from lodging therein and trailing with rotation of the paddle wheels, and the barrier 33 acts as an additional brace for the blades 27 and associated brackets 29.

The blade assemblies or units may be secured to any suitable cylindrical body portion without the need of bolting them thereto or permanently welding them thereto, they may be easily removed, as is obvious, in order to make repairs or replacements and since there need be no bolt holes drilled into a drum paddle wheel portion, the drum will not be so apt to leak.

Various changes may be made to the forms of the invention herein shown and described without departing from the spirit of the invention or scope of the claims.

What is claimed is:

1. In a blade unit for a paddle wheel having a rotating drum, straps spaced apart longitudinally of and extending about said drum, one of said straps extending about the intermediate portion of said drum, blades, each including a paddle portion and a pair of bracket portions integral with the paddle portion, each blade forming an obtuse angle in horizontal longitudinal section, with the apex of each angle disposed forwardly, and means securing said brackets to said straps, including the adjacent ends of said brackets disposed upon said intermediate strap.
2. In a blade unit for a paddle wheel having a rotating drum portion, means for encircling said drum portion, comprising spaced apart bands, blades mounted upon the outer faces of said bands, means for detachably securing said bands in tight-fitting contact with and upon the periphery of said drum portion, and water barriers extending from said periphery to said blades and from band to band.
3. In a blade unit for a paddle wheel having a

rotating drum portion, means for encircling said drum portion, comprising spaced apart bands, blades mounted upon the outer faces of said bands, means for detachably securing said bands in tight-fitting contact with and upon the periphery of said drum portion, said blades extending to said periphery and between said bands.

4. In a blade unit for a paddle wheel having a rotating drum portion, means for encircling said drum portion, comprising spaced apart bands, blades mounted upon the outer faces of said bands, means for detachably securing said bands in tight-fitting contact with and upon the periphery of said drum portion, said blades extending to said periphery and between said bands from band to band.

5. In a blade unit for a paddle wheel having a rotating drum portion, means for encircling said drum portion, comprising spaced apart straps, blades, each including a paddle portion, bracket portions extending from said paddle portion and carried upon said straps and a water barrier portion extending from said paddle portion and from bracket to bracket and having a flange section extending between said brackets and in contact with said drum, means for securing said brackets to said straps, and means for securing said straps to the periphery of said drum.

CHARLES R. MELTON.
